UNITED STATES PATENT OFFICE.

CHARLES L. RAYFIELD, OF CHICAGO, ILLINOIS, ASSIGNOR TO RAYFIELD MANUFACTURING COMPANY, OF CHICAGO, ILLINOIS, A CORPORATION OF ILLINOIS.

NOZZLE FOR OIL BURNERS.

Application filed July 20, 1925 Serial No. 44,642.

This invention relates in general to nozzles for oil burners and particularly to mechanical atomization of the oil in systems wherein the oil is supplied to the nozzle under pressure.

5 It is, therefore, an object of this invention to provide an improved atomizing nozzle that will be simple in construction and easily cleaned and adjusted for varying grades of oil and the varying capacity demands of the 10 different boilers the burner system may be applied to.

It is also an object of this invention to provide a device of the class described wherein adequate cooling of the nozzle serves to prevent 15 accumulation of partially coked fuel or carbon which would interfere with the mechanical atomization of the fuel.

Other and further important objects of this invention will be apparent from the 20 drawings in the specification and the accompanying drawings.

This invention (in a preferred form) is illustrated in the drawings and hereinafter more fully described.

25 On the drawings:

Figure 1 is a section of the airport forming the orifice for fuel and air admission to a furnace, one form of the oil spraying nozzle of this invention being shown in elevation 30 therein.

Figure 2 is an enlarged section on the line II—II of Figure 1 showing the nozzle proper in elevation.

Figure 3 is a top plan view of the nozzle 35 alone.

Figure 4 is a section on the line IV—IV of Fig. 3.

Figure 5 is a section on the line V—V of Figure 4.

40 As shown on the drawings:

The oil burning system, of which the specific form of nozzle chosen for illustration is a part, utilizes a small amount of compressed air to carry the fuel in suspension 45 along the fuel line 10 to the nozzle structure proper, so that the proportions of the nozzle passages, to be described hereinafter, are necessarily enlarged because of the accompanying air. Smaller nozzle passages would 50 therefore be used for the injection of fuel alone. The air used to carry the fuel in suspension is inadequate for proper combustion of the oil, so that the necessary air is supplied by a pipe 11 leading to a globe-like 55 casing 12 wherein the outlet 13 to the boiler

is in the form of a venturi with the nozzle outlet positioned to project beyond the throat of the venturi.

The main body 14 of the fuel nozzle is provided with cooling fins 15 which serve to prevent heating of the nozzle with consequent carbonization and gumming of the fuel oil. A hub 16 surrounds a portion of the body 14 and contains suitable passages connecting the pipe 10 to the interior of the body. The body 14 is supported in the casing 12 by the stud 17 and nut 18. An atomizing nozzle body 19 is screwed into the end of the main body 14 and is centrally apertured at 20 with a bridge 21 at its inner end to support the stem 22 of an inverted conical needle valve 23 which serves to diverge the oil spray into a flaring or conical sheet. Preferably mounted as a unit with the conical valve 23 is a plug 24 having a plurality of inclined passages 25 resembling a helical gear and adapted to give a swirling motion to the oil and air mixture passing therethrough.

Mounted on the valve stem 22 and freely rotatable thereon is a second plug 26 resembling the plug 24 with similar peripheral passages 27 which may be inclined in either direction with respect to the passages 25. The plug 26 is rapidly rotated by the force of the flowing fuel and air mixture and serves to break up the globules of oil carried by the air stream, thus materially assisting in atomizing the oil, especially the heavier grades of oil which will not vaporize without the application of an excessive amount of heat.

The valve stem 22 is adjustably mounted in the bridge 21, a lock nut 28 being provided. In practice this valve may be assembled without tightening the locknut 28 and then initially adjusted without removing the nozzle body 19 from the main body 14 and then the adjustment may be checked by a trial run. When correctly adjusted the nozzle body may be removed to tighten the lock nut 28. This 100 adjustment is provided both to care for varying types of fuel and the varying heating requirements of different boiler installations.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. A mechanical atomizing oil nozzle for oil burners comprising a centrally passaged body having a bridge at the inner end thereof, a valve stem adjustably depending from said bridge, a plug fitting the body passage and carried by said valve stem, said plug having a plurality of inclined passages therein, an inverted conical valve forming a continuation of said plug and valve stem said conical valve coacting with the body passage to form a valve and its seat, and a second plug similar to said first plug freely journaled on said valve stem adjacent said first plug.
2. In combination, in a nozzle of the class described, a nozzle body having a passageway through which liquid is discharged, a rotatable member positioned in said passageway provided with means for breaking up the liquid into drops and globules, and a fixed member positioned between said rotary member and the discharge end of said body passageway provided with means for giving the liquid a swirling motion.
3. In combination, in a nozzle of the class described, a nozzle body having a passageway, a rotatable member in said passageway provided with means for breaking up the liquid into drops and globules, a deflecting element positioned at the discharge end of said passageway provided with means for deflecting the liquid laterally from said passageway, and a fixed member between said rotary member and said deflecting element provided with means for imparting a swirling motion to the liquid prior to it being discharged from the passageway.
4. In combination, in a nozzle of the class described, a nozzle body having a passageway through which liquid is discharged, a rotatable member positioned in said passageway provided with means for breaking up the liquid into drops and globules, and a member positioned between said rotary member and the discharge end of said body passageway for giving the liquid a swirling motion, each of said members being provided with spiral grooves through which the liquid must pass.
5. In combination, in a nozzle of the class described, a nozzle body having a passageway, a rotatable member in said passageway provided with means for breaking up the liquid into drops and globules, a deflecting element positioned at the discharge end of said passageway provided with means for deflecting the liquid laterally from said passageway, and a member between said rotary member and said deflecting element provided with means for imparting a swirling motion to the liquid prior to it being discharged from the passageway, said deflecting element comprising a conical valve plug having its smallest end extending into the discharge end of said passageway.
6. In combination, in a nozzle of the class described, a nozzle body having a passageway, a rotatable member in said passageway provided with means for breaking up the liquid into drops and globules, a deflecting element positioned at the discharge end of said passageway provided with means for deflecting the liquid laterally from said passageway, a member between said rotary member and said deflecting element provided with means for imparting a swirling motion to the liquid prior to it being discharged from the passageway, said deflecting element comprising a conical valve plug having its smallest end extending into the discharge end of said passageway, and means for adjusting the deflecting valve plug so as to vary its position relative to said end of the passageway.
7. In combination, in a nozzle of the class described, a nozzle body having a passageway, a rotatable member in said passageway provided with means for breaking up the liquid into drops and globules, a deflecting element positioned at the discharge end of said passageway provided with means for deflecting the liquid laterally from said passageway, and a member between said rotary member and said deflecting element provided with means for imparting a swirling motion to the liquid prior to it being discharged from the passageway, said deflecting element comprising a valve including a conical head positioned at the discharge end of said passageway and a stem extending into said passageway and through said fixed and rotary members.
8. In combination, in a nozzle of the class described, a nozzle body having a passageway, a rotatable member in said passageway provided with means for breaking up the liquid into drops and globules, a deflecting element positioned at the discharge end of said passageway provided with means for deflecting the liquid laterally from said passageway, a fixed member between said rotary member and said deflecting element for imparting a swirling motion to the liquid prior to it being discharged from the passageway, said deflecting element comprising a valve including a conical head positioned at the discharge end of said passageway and a stem extending into said passageway and through said fixed and rotary members, and means for adjustably connecting said valve stem to said body.

In testimony whereof I have hereunto subscribed my name.

CHARLES L. RAYFIELD.
